UNITED STATES PATENT OFFICE

2,094,848

GASEOUS AND VAPOR ELECTRIC DIS-
CHARGE DEVICEWillard A. Roberts, Cleveland Heights, Ohio, as-
signor to General Electric Company, a corpo-
ration of New York

Application September 20, 1934, Serial No. 744,797

8 Claims. (Cl. 176—122)

My invention relates to gaseous and vapor electric discharge devices containing some working substance providing an ionizable atmosphere during operation, and particularly to discharge devices of the so-called "positive column" type, exemplified in gas lamps such as argon or neon lamps, and in metal vapor lamps such as sodium lamps. Very usually, sodium or other metal vapor lamps include in their working substance a small amount of easily ionized gas like neon, argon, etc. (whose partial pressure in the lamp is around 1 or 2 to 7 mm.), to assist in starting the sodium or other vapor discharge; i. e., the lamp starts as a gas lamp, and as it heats up operates more and more as a sodium vapor lamp. My invention is especially concerned with the starting of positive column devices, and is very useful in reducing or minimizing the starting voltages of such devices, and in starting relatively long tubular devices, with gaps between their terminal electrodes approaching and even very much exceeding what has heretofore appeared to be the limit for easy starting, especially in the case of low-pressure positive column alternating current glow discharge devices having "hot" or "separately heated" electron-emissive "thermionic" electrodes. Devices with so-called "cold" electrodes, heated only by the discharge, are even more difficult to start than devices with hot electrodes.

Various other features and advantages of the invention will appear from the following description of species thereof, and from the drawing.

In the drawing, Fig. 1 is a side view (with wiring diagram) of one form of tubular glow discharge lamp embodying my invention, adapted for operation on alternating current; Fig. 2 shows an axial mid-section through an electrode, on a larger scale than Fig. 1; Fig. 3 is a side view of a somewhat different lamp, adaptable to a greater over-all length than the lamp shown in Fig. 1; and Fig. 4 is a side view of still another form of lamp.

The lamp shown in Fig. 1 has a U-bent tubular glass envelope or bulb 10, although neither a U-tube nor a tubular form, even, is essential to the invention in its broader aspects. The envelope 10 contains a series of (three) rather widely spaced glow discharge electrodes 11, 12, 11 and is provided with current supply leads 13, 13 sealed into its ends. The terminal or end electrodes 11, 11, which are the main discharge electrodes, may be axially arranged in the opposite ends of the tube 10 and connected to the leads 13, 13, respectively. The intermediate elec-

trode 12, which is an auxiliary electrode, is shown midway between the main electrodes 11, 11. In this particular instance, this intermediate electrode 12 extends transversely of the tube 10 in the U-bend, and parallel with the main electrodes 11, 11, although this is not essential in all cases. The electrodes 11, 12, 11 are of the heated electron-emissive ("thermionic") type; and in the present instance, they are all indirectly heated unipotential electrodes,—each having associated with its emissive portion a heating resistance 15, connected between suitable current leads. Most simply, the current supply lead 13 to each main electrode 11 is connected to one end of its heating resistance 15 as one of the leads for the latter, as well as to the emissive portion of the electrode; and another lead 16 is connected to the other end of the resistance 15. In like manner, the intermediate electrode 12 has its heating resistance 15 connected between leads 16, 16 one of which is also connected to the electron-emissive portion of electrode 12. The lead 16 of each electrode 11 is connected (or identical) with one lead 16 of the electrode 12. In the present instance, the leads 16, 16 extend outside the envelope 10 from left-hand electrode 11 to electrode 12, and from the latter to right-hand electrode 11, being sealed through the ends of the envelope and through the outer side wall of its U-bend.

Thus all the electrode-heating resistances 15, 15, 15 are connected in series between the main supply leads 13, 13 in a "heating" circuit which as a whole may conveniently be designated C. The emissive portions of the electrodes 11, 12, 11 are connected to this circuit C at points whose differences of potential are determined by the amounts of intermediate (heating) resistance (15). Also, the circuit C as a whole is in parallel with the main long discharge gap between the main or terminal electrodes 11, 11, and likewise in parallel with the series of shorter, intermediate discharge gaps between successive electrodes in the series 11, 12, 11.

While the details of electrode construction are unessential, yet for the sake of clearness it may be pointed out that each of the electrodes 11, 12, 11 here shown (see Fig. 2) comprises a metal (nickel) base tube 17 with an external coating 18 of emissive material such as barium oxide, and shouldered insulative refractory (lava) plugs 19, 19 in the ends of the tube,—centrally bored for passage of the current leads 13, 16 (or 16, 16) to the helically coiled (tungsten) heating wire or filament 15, extending axially in the tube 17. The tube 17 is shown connected to the lead 13 or

16 by a metal (nickel) strip 20. Preferably the connection 20 of each lead 13 or 16 to the tube 17 is at the end of each electrode that is farthest from the others, as shown in Fig. 1.

5 The envelope 10 may contain a charge of sodium or other metal, and also a small amount of easily ionized gas like neon, argon, etc. And it will be understood that in practice the device 10 may be operated with such usual sodium vapor

10 lamp accessories as an enclosing vacuum jacket (not shown); a ballast resistance R (preferably of positive temperature-resistance coefficient, like the tungsten filament of an incandescent lamp), connected in series with the device to control the current rise as the device heats up after 15 starting; or a compensating resistance, reactor, or transformer (not shown), if necessary, to allow the device to be used on ordinary A. C. lighting circuits of 110 to 120 volts or the like, etc.

20 When the current is turned on to start the device, there are definite potential differences between the adjacent electrodes 11, 12, 11, whose relative magnitudes depend on the resistance between them in the heating circuit C. By using a 25 suitable supply voltage, the difference of potential across all the intermediate electrode gaps can be made greater than the ionization voltage of the starting gas used (which is 21.5 volts for neon, or 15.7 volts for argon). Supposing that 30 the effective distance or gap (around the bend of the U-tube 10) between the terminal electrodes 11, 11 materially exceeds the limit for easy starting as mentioned above, then it follows that in 35 the absence of the auxiliary electrode 12, an ionization discharge would not start in the device even after the electrodes 11, 11 had heated up and begun to emit electrons freely,—unless, possibly, under an extreme initial voltage, materially exceeding that of ordinary lighting circuits. 40 However, if the intermediate electrode gaps 11—12 and 12—11 are each well within the limit of easy starting, then separate intermediate gas 45 glow discharges will start in these intermediate gaps as soon as the electrodes 11, 12, 11 heat up sufficiently,—first in the gap with the greater 50 difference of potential across it (which for the connections of the electrode-emissive portions to the circuit C shown in Fig. 1 would naturally be the right-hand gap 12—11), and then, after the first glow discharge has started, in the other.

55 These intermediate discharges ionize the gas more or less throughout the length of the tube 10, thus creating much more favorable conditions than at the outset for a glow discharge bridging the longer gap between the main electrodes 11, 11,—which, of course, also have a greater potential difference between them than can obtain across any intermediate gap. When, moreover, the intermediate glow discharges have started in 60 all the intermediate gaps, and the discharge current increases, the current in the parallel heating resistance circuit C greatly diminishes; and so, likewise, the temperature and electron emission of the intermediate electrode 12. Accordingly, a glow discharge starts directly between the main electrodes 11, 11 under their higher potential difference; the intermediate discharges die away; and the auxiliary electrode 12 becomes 65 too cold to emit effectively, and ceases to operate. 70 This change tends to go on cumulatively, because the main electrodes 11, 11 are heated by the entire glow discharge current in the device, while the intermediate electrode 12 is heated mainly by the diminishing currents in circuit C and in 75 the glow discharges. As the device heats up and

vaporizes sufficient sodium to participate in the glow discharge, the conditions become still more favorable for the discharge between the main electrodes 11, 11, owing to the low ionization potential (5.1 volts) of sodium as compared with 5 that of neon (21.5 volts) or argon (15.7 volts). Ordinarily, however, the intermediate electrode 12 virtually ceases to operate before the characteristic sodium yellow becomes prominent in the glow discharge luminosity.

10 In this way, such a device will start on a “line” voltage less than twice its own normal operating voltage after it has heated up and reached a stable condition,—which is quite unusual for a long positive column lamp.

15 While the voltage drop along a heating resistance 15 should not be excessive, either in starting or during operation, I prefer that in starting it should sufficiently exceed the ionization potential of the atmosphere in the envelope 10, at 20 or during starting, to cause a preliminary local discharge across a relatively short gap in parallel with the resistance 15,—as between the emissive surface 18 of the electrode 11 and an adjacent part of or connected to the heating current lead 25 16,—so as to ionize enough of the atmosphere in the device to facilitate starting of the longer intermediate discharge(s). A suitably high (but not excessive) value of the heating resistance 15 is of course required, in proportion to the total 30 resistance of the heating circuit C, to take a voltage drop sufficiently exceeding the ionization potential to produce the local discharge. Undesirable persistence of the local discharge after starting of intermediate discharge(s)—or even 35 after starting of the main discharge—is prevented or minimized by the reduction of the over-all voltage on the device, by its ballast resistance R, as the total discharge current passing between the main electrodes 11, 11 increases. 40 This, however, does not necessarily require reducing the voltage along the resistance 15 actually below the ionization potential of the atmosphere in the device, after starting of the intermediate discharge(s), or even of the main 45 discharge, but only requires reducing the voltage along resistance 15 to a point where the local discharge gap is too great for such voltage to maintain an appreciable local discharge. As the operating voltage of the device is considerably lower than the starting voltage, no difficulty in operation is to be apprehended if the starting voltage on each resistance 15 is kept 50 within proper limits.

55 Fig. 3 illustrates an extension of the same principles in a longer series of (five) electrodes, by interposing an additional auxiliary electrode 12a between each of the main terminal electrodes 11, 11 and the middle electrode 12. In this instance, 60 the electrode 12 is arranged to extend along (or tangent to) the axis of the envelope 10 at its U-bend, like the electrodes 11, 11 and 12a, 12a. The current leads 16, 16, 16, 16 serially interconnecting the electrode heating resistances 15, 15, 15, 15, 15 also extend axially of the tube 10, instead of being outside it as in Fig. 1. As shown, starting anode pieces 24, 24, 24, 24 are provided on the leads 16, 16, 16, 16 closely adjacent electrodes 11, 11 and 12a, 12a: They may consist of 65 short (tungsten) wire cross-pieces welded to the (molybdenum) leads 16, 16, 16, 16. Each of these pieces 24 serves as an anode for a local “starting” discharge to the corresponding electrode 11, 11 or 12a, 12a functioning as cathode, to ionize 70 75

gas and produce conditions favorable for intermediate glow discharges between adjacent electrodes 11 and 12a and 12a and 12. They not only afford the necessary anode surfaces for the starting discharges, but limit the discharges (at starting or afterward) by their small area. Their sharp corners or points also tend to make the discharge start more easily. Preferably the leads 16, 16, 16, 16 are enclosed in insulative refractory (alumina) tubes 25, 25, 25, 25. After starting of the intermediate glow discharges between adjacent electrodes of the series 11, 12a, 12, 12a, 11 and also after supercession of these by the main discharge between electrodes 11, 11, the insulative coverings 25 on the leads 16 serve to minimize the persistence of local discharges.

With the connections shown, the greatest potential difference is between the electrode 12 and the right-hand electrode 12a, so that the first intermediate glow discharge tends to start between them, to be followed by the other intermediate glow discharges. These may be followed by a secondary intermediate glow discharge between electrode 12 and the right-hand electrode 11, 25 bridging past right-hand electrode 12a and throwing it out of operation, before the main discharge starts directly between electrodes 11, 11 and throws all three intermediate electrodes 12a, 12, 12a out of operation. Obviously, any 30 sired number (odd or even) of intermediate electrodes can be used, and their arrangement and connections can be varied.

Fig. 4 illustrates the use of a directly heated type of thermionic electrode in a positive column electric discharge device. In this particular device, the main electrodes 11, 11 are of the indirectly heated unipotential type, and only the intermediate auxiliary electrodes 12b, 12b are directly heated, consisting of finely coiled (tungsten) wires or filaments connected in series between the main, terminal electrodes 11, 11 by (molybdenum) current leads 16, 16, 16. Two such intermediate electrodes 12b, 12b are shown, though obviously a greater or less number could 45 be used. This particular lamp has a straight tubular envelope 10b, with electrodes 11, 12b, 12b, 11 and their leads 16, 16, 16 all axially arranged therein. Next to the main electrodes 11, 11, starting points 24, 24 are attached to the leads 50 16, 16, as in Fig. 3, and the leads 16, 16, 16 have insulative refractory (alumina) tubular coverings 25, 25, 25. The filaments 12b, 12b may either be bare tungsten filaments of such resistance as to be electron-emissive by incandescence when 55 the device is being started, and afterward to cool down below emissive temperature as the glow-discharge grows; or they may be coated with barium oxide to render them emissive at lower temperatures and may afterward cool down below such lower emissive temperature. Their resistances need not be the same as those of the heating filaments 15, 15 of the main electrodes 11, 11.

The operation of this device is substantially like that of those shown in Figs. 1 and 3, except that the markedly greater difference of potential across certain electrode gaps may be either more or less pronounced, owing to variation of potential along the filaments 12b, 12b themselves.

In Figs. 3 and 4, various parts and features are marked with the same reference numbers as in Figs. 1 and 2 (with added letters, where such distinction appears necessary), as a means of dispensing with repetitive description.

What I claim as new and desire to secure by Letters Patent of the United States is:

1. A positive column electric discharge device comprising an elongated, tubular envelope containing working substance providing a vaporous, ionizable atmosphere therein during operation; and a series of widely spaced electron-emissive electrodes axially mounted in said envelope each electrode having a heating resistance, the intermediate discharge gaps between said electrodes being electrically in series, said heating resistances being connected in series with one another, and in parallel with the series of discharge gaps, the connections to the respective resistances being insulated from the discharge gaps. 15

2. A positive column electric discharge device comprising an elongated, tubular envelope containing working substance providing a vaporous, ionizable atmosphere therein during operation; and a series of widely spaced, indirectly heated, 20 unipotential, electron-emissive electrodes axially mounted in said envelope, the intermediate discharge gaps between said electrodes being electrically in series, said heating resistances being connected in series with one another, and in parallel with the series of discharge gaps, the connections to the respective resistances being insulated from the discharge gaps. 25

3. A positive column electric discharge device comprising an elongated, tubular envelope containing working substance providing a vaporous, ionizable atmosphere therein during operation; a series of widely spaced, indirectly heated, unipotential, electron-emissive electrodes axially mounted in said envelope, the discharge gaps between said electrodes being electrically in series, the heating resistances for said electrodes being in series with one another, and in parallel with the series of discharge gaps; and means connecting the electron-emissive portions of said electrodes to the circuit of the heating resistances with approximately equal resistance intervening between successive points of connection in every instance but one, and with substantially greater resistance so intervening in that instance. 45

4. A positive column electric discharge device comprising an elongated, tubular envelope containing working substance providing a vaporous, ionizable atmosphere therein during operation; a series of widely spaced, indirectly heated, unipotential, electron-emissive electrodes axially mounted in said envelope, the discharge gaps between said electrodes being electrically in series, the heating resistances for said electrodes being connected in series with one another, and in parallel with the series of discharge gaps; and means connecting the electron-emissive portions of said electrodes to the circuit of the heating resistances with a heating resistance intervening 50 between successive points of connection in every instance, and with an additional heating resistance so intervening in one instance. 55

5. A positive column electric discharge device comprising an elongated, tubular envelope containing working substance providing a vaporous, ionizable atmosphere therein during operation; a series of widely spaced electron-emissive electrodes ranged along the axis of said envelope, a heating resistance for each of said electrodes, the 70 intermediate discharge gaps between said electrodes being electrically in series, and current leads extending axially of said envelope from electrode to electrode, connecting the heating resistances in series with one another, and in 75

parallel with the series of discharge gaps, and a body of insulating material on said current leads.

6. A positive column electric discharge device comprising an elongated, U-tube envelope containing working substance providing a vaporous, ionizable atmosphere therein during operation; a series of widely spaced electron-emissive electrodes axially mounted in said envelope, intermediate discharge gaps between said electrodes being electrically in series, two of said electrodes being mounted in the tube ends and an intermediate electrode being mounted in at the U-bend of said tube, and means electrically connecting the heating resistances of said electrodes in series with one another and in parallel with the series of discharge gaps, said means being insulated from the discharge gaps.

7. A positive column electric discharge device comprising an elongated, tubular envelope containing working substance providing a vaporous, ionizable atmosphere therein during operation; a series of widely spaced electron-emissive electrodes axially mounted in said envelope and having their intermediate discharge gaps electrically in series, a heating resistance for each of said electrodes, a heating circuit including said heating resistances and means for connecting said heating circuit in parallel with said discharge gaps, said heating circuit having a discharge supporting surface adjacent each of said electrodes, the short discharge gaps between said surface and said electrodes being in parallel with said resistances, respectively; the parts of said heater circuit other than said discharge supporting surfaces and said resistances being insulated from the discharge in said device, said resistances being so proportioned to the total resistance of said

heating circuit as to take voltages sufficiently exceeding the ionization potential of the atmosphere in the envelope, during starting, to produce local discharges across said short gaps and thus start discharges across the aforesaid intermediate gaps, and thereafter to take reduced voltages preventing objectionable persistence of such local discharges.

8. A positive column electric discharge device comprising an elongated, tubular envelope containing working substance providing a vaporous ionizable atmosphere therein during operation; a series of widely spaced indirectly heated unipotential electron-emissive electrodes axially mounted in said envelope having their intermediate discharge gaps electrically in series, a heating resistance for each of said electrodes, a heating circuit including said heating resistances and means for connecting said heating circuit in parallel with said discharge gaps, said heating circuit having parts in such close proximity to the emissive surfaces of said electrodes as to provide relatively short discharge gaps in parallel with the resistances, respectively; the parts of said heater circuit other than said discharge supporting surfaces and said resistances being insulated from the discharge in said device, said resistances being so proportioned to the total resistance of said heating circuit as to take voltages sufficiently exceeding the ionization potential of the atmosphere in the envelope, during starting, to produce local discharges across said short gaps and thus start discharges across the aforesaid intermediate gaps, and thereafter to take reduced voltages preventing objectionable persistence of such local discharges.

WILLARD A. ROBERTS.
